UNITED STATES PATENT OFFICE.

GEORGE ARCHER, OF MASSILLON, OHIO.

IMPROVEMENT IN COMBINED HOUNDS AND FIFTH-WHEEL.

Specification forming part of Letters Patent No. 35,662, dated June 24, 1862.

To all whom it may concern:

Be it known that I, GEORGE ARCHER, of Massillon, in the county of Stark and State of Ohio, have invented new and useful Improvements in Hounds and Fifth-Wheel Combined; and I do hereby declare that the following is a full and complete description of the construction and operation of the same, reference being had to the accompanying drawings, making part of this specification, in which—

Figure 1 is a top view. Fig. 2 is a side view; and Fig. 3 is a vertical longitudinal section in the direction of the line xx in Fig. 1.

My improvement relates to the combination of the hounds with the under section of the fifth-wheel, and the further combination therewith of the upper section of the fifth-wheel, as hereinafter specified.

A represents the forward axle-tree of a wagon. B is the bolster. C is the reach, and D is the neap or tongue.

E E represent the hounds, and F F' represent the fifth-wheel.

The hounds E E and lower section of the fifth-wheel F are made of malleable iron and cast in one piece. They may be wrought and welded together, or made from good cast metal. The hounds are separated at the forward end for the admission of the tongue D, which is secured in place by the draw-pin D', passing through the hounds and tongue. The hounds spread out toward the base and unite with the lower section F of the fifth-wheel, and forming about one-half of the circle. This section has a recess on each side of the circle, and at right angles to the slit for the tongue, for the reception of the axle-tree, as seen at a, Fig. 2.

G represents wrought-iron braces, the back ends of which are secured to the back part of the fifth-wheel section F, passing under the axle-tree, where a bolt, b, from the respective sides of the lower section F, secures them to the axle-tree, the forward ends of the braces being secured to the under side of the hounds at c, Figs. 1 and 2. The two forward ends of the hounds are secured together by a metallic strap, d, which passes over the tongue and forms a support and point of draft for the doubltree.

The upper section F of the fifth-wheel is circular, with a small groove running around the under side, as seen at e, to admit the heads of the bolts, there being a like groove in the section F. The upper section F' is secured to the bolster by two bolts, b' b', and to the reach by two others, b'' b'', placed at right angles to the former. Upon the forward and inner edge of the lower section F is secured an iron clamp, h, Fig. 3, which hooks over the inner edge of the section F' to keep the two parts in contact. The king-bolt G' passes through the center of the bolster, the center of the circle F F', and through the axle-tree, thus forming the center of motion for the fifth-wheel.

What I claim as my improvement, and desire to secure by Letters Patent, is—

The herein-described special construction and arrangement of the hounds and fifth-wheel, when combined and operating conjointly, as specified.

GEORGE ARCHER.
